Primary Examiner — Terry A Wallace(74) *Attorney, Agent, or Firm* — WHGC, P.L.C.; John F. O'Rourke(57) **CLAIM**

The ornamental design for a thermal insulated cup with dual-well dock, as shown and described.

DESCRIPTION

This application is related to co-pending utility patent application, U.S. application Ser. No. 16/045,538, entitled, Thermal Insulated Mug with Dual Well Dock, filed Jul. 25, 2018. FIG. 1 is a top/front perspective view of the complete assembly showing our new design;

FIG. 2 is a top/front perspective view of the complete assembly in an exploded configuration thereof;

FIG. 3 is a top/rear perspective view of the complete assembly in an exploded configuration thereof;

FIG. 4 is a bottom/front perspective view of the complete assembly in an exploded configuration thereof;

FIG. 5 is a bottom/rear perspective view of the complete assembly in an exploded configuration thereof;

FIG. 6 is a right-side elevation view of the complete assembly in an exploded configuration thereof;

FIG. 7 is a left-side elevation view of the complete assembly in an exploded configuration thereof; and,

FIG. 8 is a top/front perspective view of a complete assembly in an alternative configuration.
